UNITED STATES PATENT OFFICE.

JAMES W. GAUGHAN, OF SOUTH OMAHA, NEBRASKA, ASSIGNOR TO FOUR WHEEL DRIVE AUTO CO., OF CLINTONVILLE, WISCONSIN, A CORPORATION OF WISCONSIN.

PROTECTING DEVICE FOR BALL-AND-SOCKET AXLE-JOINTS.

1,176,748.

Specification of Letters Patent.

Patented Mar. 28, 1916.

Application filed September 16, 1912. Serial No. 720,543.

To all whom it may concern:

Be it known that I, JAMES W. GAUGHAN, a citizen of the United States, residing at South Omaha, county of Douglas, and State of Nebraska, have invented new and useful Improvements in Protecting Devices for Ball-and-Socket Axle-Joints, of which the following is a specification.

My invention relates to improvements in 10 protecting device for a ball and socket axle joint.

The object of my invention is to provide means whereby a flexible covering may be applied to the members of a ball and socket 15 pivot joint so as to exclude dust and grit from the bearing faces.

In the drawing, Figure 1 is an elevation showing my invention applied to the stub- 20 axle of a motor driven vehicle. Fig. 2 is a 20 sectional view of the same drawn longitudinally to the axle.

Like parts are identified by the same reference characters in both views.

The stationary member A of the axle, in 25 my improved structure is provided with a spherically curved bearing member B which carries upwardly and downwardly projecting pivot posts C. A spherically curved bearing member D is adapted to fit over the 30 member B and is provided with upwardly and downwardly projecting sleeves E which receive the posts C, said posts being covered by caps F. The specific structure of this bearing is shown and described in a separate 35 application and need not be more specifically described herein. It will be observed, however, that the metal parts of the member D completely cover member B and exclude dust and grit therefrom except at 40 the opening in that side of the member D through which the axle A extends. At this side the member D is not only provided with an opening of sufficient size to permit the member A to pass through it, but said opening 45 must also be large enough to allow member D to oscillate upon the pivotal axes of the posts C. To prevent dust and grit from entering the bearing through this opening in the member D I employ a flexible covering 50 G, preferably of leather, and secure the same to the members A and D respectively. Where this covering incloses the axle member A it is cylindrical in form and is secured to the axle member A by an ordinary ring H. The covering G is conically ex-

panded, however, and its outer margins I are curved and are adapted to fit the spherically curved surface of the member D at a point back of the margin K of the opening therein. This end or marginal portion of 60 the covering G is secured to the member D by a band L which conforms in shape to the marginal portion of the outer end of the covering G and to the curvature of the member D along the line thereof to which it is applied. The band L must, therefore, have an interior conically tapered surface of irregular contour, the inclination of which changes as the band curves inwardly at the sides in order to allow for the transverse elongation 70 of the opening in the member D, said band curving outwardly at the top and the bottom in order to pass around the pivot sleeves E and parts connected therewith such as the steering eye M. The collar H and band L 75 are secured in position by bolts or rivets, preferably by bolts N. The covering G, will, of course, be somewhat compressed between the band L and collar H, whereby sufficient slack is provided to allow flexion of the 80 joint.

I claim:

1. A dust tight ball and socket axle joint for driving and steering mechanisms, including mutually engaging ball and socket 85 members provided respectively with interacting steering pivot pins and closed pin receiving sockets, said socket member having an opening through which the ball carrying member projects, in combination with a 90 flexible dust excluding covering encircling both members and secured thereto on all sides in a position to completely cover and seal said opening, said covering being expanded intermediate of its ends, to provide 95 sufficient slack to permit relative swinging movements of the ball and socket members upon each other, a flat clamping band encircling said covering and the ball carrying member in close proximity to the ball, and a 100 co-operative clamping band connecting the expanded portion of the covering with the socket member along a curved line substantially conforming to the arc of a small circle of the socket member, said clamping 105 band conforming to the surface of the socket member to which it is supplied, substantially as described.

2. The combination with a set of mutually engaging spherically rounded bearing mem- 110

2

bers, of an axle member connected with the inner bearing member and projecting through a transversely elongated opening in the other member, a flexible covering for said opening conically tapered and formed at one end to receive the axle member and enlarged at the other end to receive the exterior bearing member, a clamping ring binding said covering to the axle member, and a band 10 binding said covering to the exterior surface of the exterior bearing member, the band encircling said bearing member adjacent to said opening and conforming to the surface thereof along a line which diverges from a 15 circle in the face of the outer member by

having inwardly curved portions conforming generally to the inwardly curving margins of the laterally extended opening, and clamping bolts for binding the ring and band upon the flexible covering and to the 20 axle member and bearing member respectively, substantially as described.

In testimony whereof I affix my signature in the presence of three witnesses.

JAMES W. GAUGHAN.
